UNITED STATES PATENT OFFICE.

JOHN H. WILLIAMS, OF WESTWOOD, CALIFORNIA.

DESIGN FOR A KNIFE.

Application filed December 17, 1927. Serial No. 24,705. Term of patent 14 years.

To all whom it may concern:

Be it known that I, JOHN H. WILLIAMS, a citizen of the United States, residing at Westwood, in the county of Lassen and State of California, have invented a new, original, and ornamental Design for a Knife, of which the following is a specification, reference being had to the accompanying drawing, forming part thereof.

I claim: The ornamental design for a knife, as shown.

JOHN H. WILLIAMS.
